UNITED STATES PATENT OFFICE

WILLIAM R. UHLEMANN, OF EVANSTON, ILLINOIS

DESIGN FOR A LENS MOUNTING OR THE LIKE

Application filed March 29, 1930. Serial No. 35,065. Term of patent 14 years.

To all whom it may concern:

Be it known that I, WILLIAM R. UHLEMANN, a citizen of the United States, residing in Evanston, county of Cook, and State of Illinois, have invented a new, original, and ornamental Design for Lens Mounting or the like, of which the following is a specification, reference being had to the accompanying drawing, forming a part thereof.

Fig. 1 is a front view of a lens mounting showing my new design; the broken lines merely show the association of the design when in use; and Fig. 2 is a top plan view thereof.

I claim:

The ornamental design for a lens mounting or the like, substantially as shown.

WM. R. UHLEMANN
